SINKER CARRIER FOR FLAT KNITTING MACHINES

Filed March 7, 1949

FIG. 1.

FIG. 2.

FIG. 3.

Inventor:

Richard Parthum

This invention relates to an improvement in the construction of a sinker carrier for flat knitting machines, and more particularly to a carrier for a single sinker.

UNITED STATES PATENT OFFICE

2,562,435

SINKER CARRIER FOR FLAT KNITTING MACHINES

Richard Parthum, Orholm, Denmark

Application: March 7, 1949, Serial No. 79,986
In Sweden March 17, 1948

1 Claim. (Cl. 66—110)

1

The present invention relates to an improvement in the construction of a sinker carrier for flat knitting machines.

In such knitting machines the sinkers are inserted between an upper and a lower carrier part that have transverse grooves in which the sinkers are guided. These grooves are cut very carefully as well with reference to their depth as to their relative spacing, and the carrier parts are therewith assembled by means of screws at each end. To obtain a correct interspacing of the lower and upper carrier members distance members are inserted between the ends of the carrier parts. It is absolutely necessary for proper operation of the knitting machine that all the sinkers slide easily within the grooves without any play whatever. Between the screws at each end of the carrier a number of clamping members are arranged in such a manner that any upward bend of the upper carrier member between the end clamping screws is prevented.

These intermediate clamping members may to some extent be employed for tightening up to compensate wear, but such a tightening up will result in a downward bending of the upper carrier part, and consequently regulation can only take place about the middle of the carrier. The curvature of the upper carrier part will furthermore result in an alteration of the vertical position of some of the sinker grooves, and the sinkers guided by these grooves will become more or less deformed. In order to make up for wear it is therefore necessary to remove all the clamping members, lift the upper carrier part and reduce the spacing members until the proper spacing between the carrier parts is obtained.

The object of the present invention is to render such a dismantling of the sinker carrier unnecessary, thus saving considerable time in the correction of faults in the operation of the sinkers.

A further object is to provide means by which it is possible in a simple manner to obtain a more correct adjustment of the carrier parts in relation to the sinkers than has hitherto been possible.

A still further object of the invention is to provide means which in a simple manner render possible a rapid adjustment of the carrier parts in order to reduce the deformation of the sinkers due to wear.

Other objects and a fuller understanding of the invention may be had by referring to the following description taken in conjunction with the accompanying drawing in which like references are applied to like parts in the various figures, and in which

the right-hand carrier member, carrying a single sinker, is shown in the upper part of the drawing, and the left-hand carrier member, carrying a number of sinkers, is shown in the lower part of the drawing.

2

Fig. 1 is a vertical section through a sinker carrier in a flat knitting machine showing a single sinker inserted between the upper and lower carrier parts.

5 Fig. 2 is a top elevation of the sinker carrier on an increased scale and

Fig. 3 is a section on line III—III in Fig. 1 shown on an enlarged scale.

Referring to the drawing, only such parts of 10 a flat knitting machine that have direct relation to the invention are shown. Thus 1 indicates the upper part of the sinker carrier, and 2 indicates the lower carrier part broken away from the remainder of the machine. Between these carrier parts a number of sinkers 3 are disposed in transverse grooves formed in the opposed surfaces of the carrier parts. The two carrier parts 1 and 2 are assembled by means of a screw 4 at each end of the carrier, which screws are inserted 15 through holes in the upper carrier part 1 and screwed into threaded holes in the lower carrier part 2. Between the two end screws 4 a number of clamping members of a peculiar construction are arranged. These intermediate clamping 20 members are shown in Fig. 3 and comprise each a thin metal strip 5 inserted between two sinkers and attached by its one end to a head 6 inserted in a recessed hole in the lower surface of the lower carrier member 2, while the opposite end 25 of the metal strip 5 is attached to a threaded pin 7 inserted within a smooth hole in the upper carrier member 1 and provided with a nut 8 by means of which the threaded pin 7 can be adjusted in order to regulate the tension of the 30 assembled clamping screw 5, 6, 7.

According to the invention the upper sinker carrier part 1 is at each end provided with a number, e. g. four threaded holes penetrating the carrier part. Into each of these holes is 35 screwed a slotted screw 9 that abuts the upper surface of the lower carrier part 2. Preferably these four screws 9 at each end of the carrier are arranged relatively spaced around the clamping screw 4 applied to the end of the carrier 40 member in question, e. g. pair-wise at either side of the screw 4.

In case any irregularities occur in the displacement of the sinkers 3 between the upper and lower carrier parts 1 and 2 resulting in poor 45 knitting, it is possible by loosening the clamping screws 4 and thereupon adjusting one or several of the slotted screws 9, to readjust the relative position of the upper and lower carrier parts 1 and 2, and in this manner regulate the guiding 50 of the sinkers until they all operate in their proper manner so that the formation of loops

during the knitting becomes normal. After adjustment by means of the screws 9, the clamping screws 4 are again tightened, and owing to the presence of the screws 9 there will be no risk of tightening the carrier parts 1 and 2 too much, as likewise it is unnecessary to take the carrier members apart in order to carry out a readjustment.

I declare that what I claim and desire protected by Letters Patent is:

In a sinker carrier for flat knitting machines, the combination of two superimposed elongated carrier parts provided with transverse grooves in their opposed surfaces, sinkers arranged for reciprocal displacement within the grooves, screws for assembling the carrier parts at each end thereof, interspaced clamp members disposed between the said end screws to assemble the inter-

mediate portion of the carrier parts, and in each end of the upper carrier part four adjustment screws arranged in pairs at either side of each end screw and screwed through the said upper carrier part to abut the upper surface of the lower carrier part.
